VIBRATORY CONVEYER AND SCREEN

Filed Dec. 31, 1938

UNITED STATES PATENT OFFICE

2,251,678

VIBRATORY CONVEYER AND SCREEN

Arthur D. Holt, Columbus, Ohio, assignor to The
Traylor-Vibrator Company, a corporation of
Colorado

Application December 31, 1938, Serial No. 248,768

2 Claims. (Cl. 209—247)

This invention relates to a vibratory conveyer or feeder and screen or grating adapted to feed material and effect a size classification thereof.

An object of the invention is to provide a feeder or conveyer of the above mentioned type in which the screening component of vibratory motion is greater with respect to the screening surface or grating than with respect to the conveying surface.

Another object of the invention is to provide an improved screen, grating or grizzly of rugged construction.

Other objects of the invention will appear hereinafter, the novel features and combinations being set forth in the appended claims.

In the accompanying drawing,

Fig. 1 is a side elevational view of the device of my invention;

Fig. 2 is a front view of the deck thereof; and

Fig. 3 is a schematic view showing by vectors the relative components of motion of the deck of the conveying surface and the screening surface.

I have found in practice that where a screen, grating or grizzly is provided adjacent the end of the deck of a vibratory feeder this screen, grating or grizzly will operate more efficiently if the screening component of motion or the component of motion at right angles to the general plane thereof is increased over that customarily employed to effect the conveying action over the conveying surface of the feeder. The combined conveyer or feeder and screen, grating or grizzly comprising my invention incorporates structure which produces this improved result.

Referring to the accompanying figures of the drawing it is to be seen that I have provided a device comprising a deck or pan 10 having appropriate side walls 11, 11, a sloping rear wall 12 and an imperforate material supporting and conveying bottom 13. As illustrated in the drawing, the imperforate bottom 13 is concavely curved, but this is not essential as it may be flat or may be convexly curved.

Adjacent the forward end of the deck 10 and positioned to receive material which is discharged over the forward or discharge end of the imperforate bottom 13 is a screen, grating or grizzly 14. This screening, grating or grizzly 14 comprises a plurality of substantially parallel spaced bars 15 which are generally of tapered construction, the tops of which progressively decrease in width from the top of the grating to the bottom thereof, as clearly illustrated in Fig. 2 of the drawing.

The spaced bars 15 are placed on edge and near their rear ends are permanently attached, as by welding, to a cross-piece in the form of a bar 16 to which are rigidly attached, as by welding, end plates 17 adapted to be rigidly but removably attached to the side walls 11 of the deck 10 by removable bolts 18. Adjacent their forward ends the bars 15 are welded to a cross-piece in the form of a bar 20 having end plates 21 adapted to be attached to the side walls 11 of the deck 10 as by bolts 19.

By reference to Fig. 1 of the drawing it is to be particularly noted that the general plane of the screen, grating or grizzly 14 slopes downwardly from the general plane of the imperforate bottom 13 and in the drawings this angled slope is shown as 20 degrees. It is to be understood, however, that this angle may be other than 20 degrees either in a positive or negative direction.

In order to convey material over the bottom 13 and over the screen, grating or grizzly 14 the deck 10 is operated by a vibratory electro-magnetic motor 22, the structure of which is disclosed in more complete detail in the application of James A. Flint for a Vibratory feeder and screen, Serial No. 73,318, filed April 8, 1936.

Briefly described, the vibratory motor 22 comprises a main frame or main casting 23 having an elongated transversely extending slot 24 through which extends a plurality of stacked spring bars 25, the opposite ends of which are rigidly clamped in said main frame 23. To the centers of the spring bars 25 there is clamped a vibratory armature shaft 26 which has a cross-head removably attached to the deck 10 as by bolts 27. The rear end of the armature shaft 26 is provided with a bracket 28 carrying an armature 29 preferably made of laminated steel which is adapted to be attracted by a field structure 30 including a U-shaped core 31 which is energized by a pair of coils 32 carried by brackets 33. The field structure 30 is adjustably supported by adjusting bolts 34 on a pair of U-shaped brackets, one of which is seen at 35, which brackets are rigidly attached at their bottoms or upper ends to the main frame 23. The main frame 23 is also provided with resiliently mounted supporting legs one of which is seen at 36. Also interconnecting the rear end of the deck 10 and the armature shaft 26 is a bracket 37 which substantially reduces the twisting torsion on the bars 25. The forward end of the deck 10 is resiliently supported by a pair of spring supports, one of which is seen at 38.

In the operation of the device, the material to be fed or conveyed and screened is delivered to the deck 10 preferably adjacent the rear wall 12 and onto the imperforate bottom 13. Vibratory motion imparted to the deck 10 by the vibratory motor 22, which is energized with either alternating, mixed or rectified pulsating current, is along the rectilinear axis of the armature shaft 26 which axis makes an acute angle with the general plane of the imperforate bottom 13. This angle may be at any value between relatively wide limits and in the drawing it is illustrated as approximately 20 degrees. The action of the deck 10 under the influence of the vibratory motor 22 to convey and screen material will be clearly understood by reference to Fig. 3 of the drawing.

The imperforate bottom 13 is diagrammatically illustrated as substantially horizontal and the screen, grating or grizzly 14 is diagrammatically illustrated as inclined thereto at an angle of 20 degrees which, as aforesaid, may be varied. The vibratory motions of the imperforate bottom 13 and the screen 14 are represented by the parallel vectors M and M', respectively. These vectors M and M' will, of course, have the same value and direction because any point on the deck 10 will have the same amplitude of vibratory motion since the deck vibrates rectilinearly. It is evident, however, that the horizontal component of the vector M with respect to the general plane of the imperforate bottom 13, which is seen at H, is greater than the horizontal vector H' with respect to the plane of the screen 14. Also, the vertical component V of the vector M is less than the vertical component V' of the vector M'.

The conveying action of the imperforate bottom 13 and the screen 14 is, of course, due to the fact that there are both vertical and horizontal components with respect to the planes of each in the vibratory motion of the deck 10.

It is common to designate the horizontal components H, H' as the conveying components because the values of these components determine, at least to a large extent, the amount of conveying action which is realized. Likewise, the upright components V and V' are commonly designated the screening components because they are largely effective to force material through a screen provided there is a screen present. It is, of course, to be understood, however, that some vertical component is necessary to produce the conveying action on the imperforate bottom 13, if it is horizontally positioned.

Since the upright component V' is greater than the vertical component V it is evident that there is a greater proportion of screening action derived from the vibratory movement on the screen, grating or grizzly 14, where it is desired, than on the imperforate bottom 13 where it may be relatively small since no screening action is here effected. In other words, by sloping the screen, grating or grizzly 14 with respect to the imperforate bottom 13, the vibratory motion of the deck 10 produces a greater screening component of movement over the screen, grating or grizzly 14 where it is desired, to effect a screening action, than over the imperforate bottom 13 where no screening action takes place. As a consequence, there will be a more efficient screening of the material in passing over the screen, grating or grizzly 14 than if it were parallel with the imperforate bottom 13.

As above pointed out, some vertical compo-

nent is necessary to effect the conveying action on the bottom 13 and this, of course, is desirable if the bottom 13 is to be placed horizontally, as it frequently is in practice. However, the ma-

5 jor portion of the conveying action is due to the component H. When the screen, grating or grizzly 14 is reached it will substantially always be sloping downwardly and for this reason it is 10 not essential that any conveying component H' 15 at all be present because gravity alone will cause material to flow over this screen, grating or grizzly 14 particularly if it is vibrated and this vibratory motion may be entirely vertical with respect to the general plane thereof.

15 In other words, I may slope the screen, grating or grizzly 14 so that it is substantially at right angles with the longitudinal axis of the armature shaft 26 or, in other words, at right angles to the vectors M and M'. It is, of course, evident 20 that in such a case the vectors M' and V' will coincide or, in other words, all of the vibratory motion as measured from the plane of the screen, grating or grizzly 14 will be at right angles thereto and produce a screening action.

25 It is thus to be seen that when material is fed to the apparatus of my invention it will be conveyed along the imperforate bottom 13 which may be horizontal, upwardly sloping or downwardly sloping, from which it will discharge 30 over the front end thereof onto the screen, grating or grizzly 14 by which it will be screened with the large particles of material discharging over the lower end of said screen, grating or grizzly 14 and the smaller particles passing therethrough.

35 Furthermore, the screening component of the vibratory motion will be greater with respect to the screen, grating or grizzly 14 than with respect to the bottom 13, thus insuring a very efficient screening action on the material to remove all of the under-size.

40 In addition, the slope of the screen, grating or grizzly 14 will increase the velocity of material flow thereover, thus thinning it out and aiding in effecting an efficient screening thereof. There is 45 another important action produced by this sloping of the screen, grating or grizzly 14, which prevents clogging and insures removal of the fines. As the material leaves the bottom 13, it breaks open which breaking is followed by the 50 thinning out on screen 14. This is very important, particularly with material that tends to matt during conveying, as it insures free movement of the fines through the screen 14. It is also an important factor that the very rapid 55 vibratory movement of this type of conveyer tends to classify the material as to size, with the fines in the bottom stratum.

Obviously those skilled in the art may make 60 various changes in the details and arrangement of parts without departing from the spirit and scope of the invention as defined by the claims hereto appended, and I therefore wish not to be restricted to the precise construction herein disclosed.

65 Having thus described and shown an embodiment of my invention, what I desire to secure by Letters Patent of the United States is:

1. In a vibratory feeder and screen, the combination with a frame, of an imperforate deck 70 mounted thereon, a bar screen mounted on said frame in position to receive material from said imperforate deck, and an electro-magnetic motor connected to said frame to vibrate the same rectilinearly along lines making acute angles with the deck and the bar screen, each forward move-

ment in the direction of flow having an upward component of movement and a horizontal component of movement and the bar screen having two components of movement one normal and screening and the other parallel and conveying, the normal component for the bar screen being greater than the upward component for the deck due to the rectilinear vibrations produced by said motor and the downward slope of the bar screen.

2. In a vibratory feeder, the combination with a supporting frame, of a material receiving and conveying deck thereon with an imperforate bottom, of a grating adjacent the discharge end of

5 said deck and sloping downwardly therefrom, and an electro-magnetic motor having an armature rigidly secured to said frame to effect vibrations of said deck and said grating along rectilinear lines making acute angles with the direction of flow of material over said deck and said grating, each forward movement of the deck having a vertical component and a forwardly extending horizontal conveying component and each forward movement of the grating having a normal screening component greater than the aforesaid vertical component.
